UNITED STATES PATENT OFFICE.

CLIFFORD G. ARMSTRONG, OF MERIDEN, CONNECTICUT, ASSIGNOR OF ONE-HALF TO
HERBERT C. ARMSTRONG, OF MERIDEN, CONNECTICUT.

SAFETY DEVICE FOR FOOT-POWER PRESSES.

Application filed March 2, 1927. Serial No. 172,035.

This invention relates to improvement in safety devices for foot power presses, that is, devices which will arrest the movement of the ram in the event of the hand or fingers of the operator being in the path thereof on the downward thrust. The object of the invention is to provide simple means which may be readily attached to presses of usual construction, which will be positive in action and in no wise interfere with the regular operation of a press, and the invention consists in the construction as hereinafter described and particularly recited in the claims.

In the accompanying drawings:

Fig. 1 is a front view of a safety device constructed in accordance with my invention and shown as applied to a press with the parts in their normal positions;

Fig. 2 is a side view of the same;

Fig. 3 is a front view with the guard-lever shown in broken lines and showing the bolt in its thrust position, in which the ram is locked;

Fig. 4 is a similar view showing the parts in the normal position, just as the bolt-latch

has been tripped;

Fig. 5 is a sectional view on the line 5—5 of Fig. 1;

Fig. 6 is a perspective view of the guard-lever detached;

Fig. 7 is a perspective view of the bolt-latch detached;

Fig. 8 is a perspective view of the bolt detached; and

Fig. 9 is a perspective view of the bolt-carrying block detached, showing the upper end of the guideway secured thereto.

In carrying out my invention, I employ a guard 10 formed from sheet-metal and of the required form for use on the press to which it is applied. This guard is adjustably connected with a vertically-arranged slide 11 which moves between guideways 12 and 13 attached to a block 14 which, in turn, is screwed to the ram 15 which is mounted in a press-frame 16 and operated by a lever 17, which is usually moved by a treadle, not shown. Secured to the face of the frame 16 opposite the guideways 12 and 13, is a rack 18 formed with notches 19, 20, and 21, more or less in number. Mounted in the block 14 for transverse movement is a bolt 22 provided with a beveled nose 23 and a locking-notch 24. The bolt is also provided at its end with guide-pins 25 extending through a guide-

block 26 formed integral with or attached to the block 14, and around these pins are springs 27 which tend to move the bolt forward. The bolt is normally held in its re-tired position by a pivotal bolt-latch 28 which is pivoted to the block 14 and formed with a locking-notch 29 to engage with the edge 30 of the notch 24 in the bolt. Carried by this latch-bolt is a stud 31 which enters a cam-groove 32 in a guard-lever 33, which is pivotally connected to the face of the rack 18, and connecting the free end of this lever with the guard-slide 11 is a link 34, so that when the ram rises, the guard will be lifted above the work-bed or anvil 35. A spring 36 will be connected to the free end of the lever 33, the lower end of the spring being fixed to the guideways. Instead of employing the springs 27, or in addition thereto, I may employ a bolt-lever 37 provided at its outer end with a weight 38, the tendency of this lever and weight being to throw the bolt forward in the same way as the springs 27.

Under normal conditions and as shown in Fig. 1 of the drawings, the bolt is held in its re-tired position by the bolt-latch 28, so that the ram is free to be moved down and up as required. The stud 31, traveling freely in the cam-groove 32, will, on the upward movement of the ram, move the guard-lever upward and raise the guard above the work-bed 35, so as to give free access thereto, but should the fingers be in the path of the guard-lever 33 on the downward movement, further downward movement of the guard is arrested and, through the link 34, lifts the guard-lever 33, causing the point 39 formed by the cam-groove 32 to be moved into the path of the stud 31 of the bolt-latch 28 and lift that latch out of the path of the bolt 22, allowing the bolt to move forward under the action of the springs 27 or bolt-lever 37, or both, and enter one of the notches 19, 20 or 21 in the rack 18 and thus lock the ram against further downward movement. Owing to the leverage and freedom of movement of the parts, this tripping will take place with but slight pressure upon the fingers by the guard 10.

To restore the parts to the normal position, it is only necessary to raise the ram which, owing to the inclined surfaces of the notches in the rack, will force the bolt rearward into position to be engaged by the bolt-latch 28. Preferably, a bolt-stop 40 will cross the bolt-

recess 41 in the block 14 and the bolt will be provided with a clearance-space 42 for this stop.

It will thus be seen that I have provided, in 5 a very simple manner, a safety device for presses which will be positive in its action and arrest the movement of the ram in case the hands or fingers of the operator are in the path of the ram.

10 I claim:

1. A safety device for foot power presses, comprising a guard, a slide to which the guard is attached, a guideway for said slide arranged vertically at one side of the ram, a 15 block connected with the ram of a press, said guideways connected with said block, a rack secured to the frame on the opposite side of the ram, a longitudinally-movable bolt mounted in said block, means tending to 20 throw the bolt forward, a latch for holding said bolt in its retired position and provided with a stud, a guard-lever pivotally connected with the said rack and formed with a cam-slot into which the said stud extends, and a 25 link connecting said guard-lever with said slide.

2. A safety device for foot power presses, comprising a guard, a slide to which the guard is attached, a guideway for said slide 30 arranged vertically at one side of the ram, a block connected with the ram of a press, said guideways connected with said block, a rack secured to the frame on the opposite side of the ram, a longitudinally-movable bolt 35 mounted in said block, a spring tending to throw the bolt forward, a latch for holding said bolt in its retired position and provided with a stud, a guard-lever pivotally connected with the said rack and formed with a cam-slot into which the said stud extends, and a link connecting said guard-lever with said slide.

3. A safety device for foot power presses, comprising a guard, a slide to which the 45 guard is attached, a guideway for said slide arranged vertically at one side of the ram, a block connected with the ram of a press, said guideways connected with said block, a rack

secured to the frame on the opposite side of the ram, a longitudinally-movable bolt 50 mounted in said block, means tending to throw the bolt forward, a latch for holding said bolt in its retired position and provided with a stud, a guard-lever pivotally connected with the said rack and formed with a cam-slot into which the said stud extends, a link connecting said guard-lever with said slide, and a spring tending to draw the free end of the guard-lever downward.

4. A safety device for foot power presses, 60 comprising a guard, a slide to which the guard is attached, a guideway for said slide arranged vertically at one side of the ram, a block connected with the ram of a press, said guideways connected with said block, a rack 65 secured to the frame on the opposite side of the ram, a longitudinally-movable bolt having a beveled nose mounted in said block, means tending to throw the bolt forward, a latch for holding said bolt in its retired position and provided with a stud, a guard-lever pivotally connected with the said rack and formed with a cam-slot into which the said stud extends, and a link connecting said 70 guard-lever with said slide.

5. A safety device for foot power presses, comprising a guard, a slide to which the guard is attached, a guideway for said slide arranged vertically at one side of the ram, a block connected with the ram of a press, said guideways connected with said block, a rack 80 secured to the frame on the opposite side of the ram, a longitudinally-movable bolt having a beveled nose and a locking-notch mounted in said block, means tending to throw the bolt forward, a latch for holding said bolt in its retired position and provided with a stud, a guard-lever pivotally connected with the said rack and formed with a cam-slot into which the said stud extends, 85 and a link connecting said guard-lever with said slide.

In testimony whereof, I have signed this specification.

CLIFFORD G. ARMSTRONG.
